CAR CONSTRUCTION

David Hindahl, Chicago, Ill., assignor to Harry S.
Hart, Chicago, Ill.Application August 12, 1933, Serial No. 684,845
Renewed March 6, 1935

17 Claims. (Cl. 105—409)

This invention relates to a new and improved car construction and more particularly to a car wall construction especially adapted for use in connection with cars of the hopper type.

5 The new and improved car wall construction of this invention produces the combined advantages of maximum capacity and externally positioned side wall stakes and although the invention is intended for application for newly built 10 cars, it is also adapted for application to cars of a type now in existence having inside stakes whereby through the application of this invention to such cars, new and improved wall constructions may be provided without altering the under 15 structure nor the bottom chords of the car, but by merely applying and attaching the newly constructed walls.

In cars of the hopper type, the load containing capacity is limited by the clearance diagram of 20 the cars together with the standard height of the top of the hoppers. The hopper walls are constructed of metal plates and in order to provide the requisite strength, the plates are supported by vertically extending stakes located along the 25 side and end walls. The stakes are attached to top and bottom chords which with the stakes constitute the wall frame construction. Heretofore in endeavoring to increase the capacities of cars of this type, some have been built with the stakes 30 mounted inside of the car walls, which enables the placement of the wall plates in the maximum outward position permitted by the limiting dimensions for car width. Such construction however, produces a serious disadvantage in that it exposes 35 the side stakes to wear and damage and deterioration by rust. The material carried in the car wears against the stakes in loading and unloading and the protective painting is worn off which exposes the stakes to the moisture in the load 40 with the resulting deterioration and damage.

This objection is very serious because the stakes constitute a vital part of the supporting frame construction and damage thereto constitutes a serious impairment of the strength and serviceability of the car in use. Furthermore, whereas the wall plates can be replaced relatively cheaply and by simple operations, the replacement of the stakes as a part of the car frame is an expensive and more difficult operation. Besides wear and 45 deterioration of the plates does not weaken or impair the supporting frame structure of the car.

It will therefore appear that the designers and builders of cars have been confronted with two conflicting difficulties, the first of which is the 50 objection to less than maximum capacities as

occasioned when the stakes are placed on the outside of the walls in order to provide the desired protection for the stakes, and, secondly, the undesirable damage and deterioration of the stakes as a part of the car frame when the stakes are placed on the inside of the car walls so as to afford the maximum capacity produced when the wall plates are positioned approximately in the plane of the outer limiting dimensions of the car.

Prior to this invention cars of both types have been constructed and used by the railroads. In those instances where maximum capacity was less important, the stakes were placed externally for the protection benefit but with a considerable sacrifice in load capacity. In recent years, however, increased capacity has become more important with the result that more recent designs provide for outwardly placed walls and internally placed stakes whereby the maintenance and strength of the car frame is sacrificed and damage 20 and deterioration of the stakes is suffered in order to secure the wanted advantage of increased capacity.

The bottom supporting chord of car constructions of this type are usually of angle cross-section having a vertical flange placed in the proper plane to permit the ready attachment thereto of the bottom ends of the wall stakes while at the same time providing a longitudinally extending attachment for the lower edges of the side wall plates. Accordingly, those cars of reduced capacity having outside stakes have been provided with lower chords as a part of their under construction which are placed slightly inwardly of the maximum outside plane of the car so as to abut against the inner surface of the side stakes and serve as an attaching flange for the bottom end of the wall plates. In this case the bottom frame chords were placed inwardly by the depth 25 of the car stakes. On the other hand, those cars having maximum capacity with the stakes on the inside have been designed with bottom chords placed outwardly so that the vertical flange thereof would abut against the outside surface of the stakes and provide attaching flanges for the side wall plates placed substantially in the plane of the maximum width dimension of the car.

Prior to this invention, effort has been made to overcome the problems above presented and to devise a construction for cars which would embody both advantages of capacity and protection so that the stakes could be placed externally to provide the desirable protection while at the same time, the wall plates could be positioned in the plane of the maximum width of the car so as to 30 35 40 45 50 55

provide a maximum capacity. Such construction affords both advantages without the disadvantages previously attending such benefits.

Such a construction is disclosed and claimed 5 in Patent No. 1,623,591, issued April 5th, 1927, to Harry S. Hart, the assignee of this application. The disclosure of this patent however, shows and describes a car having an underframe of the type designed for external stakes or in other words, 10 a car having an underframe of the early design as for cars of reduced capacity with wall plates on the inside of the stakes and with lower frame chords disposed inwardly from the plane of maximum permissible width.

15 By referring to the disclosure of said patent it will be noted that the wall plates are provided at their bottom edges with inturned portions for attachment to the vertical flange of the bottom chord so that a relatively simple and efficient 20 construction is provided with all of the marginal attaching portions of the wall plates disposed in an inner plane to conform to the manner of attaching the inwardly disposed plates of the prior car designs but with their central portions 25 deflected outwardly to occupy a position substantially in the plane of the outer dimension of the car.

However, the teachings of said patent do not readily apply to the type of car having underframes constructed for inside stakes which have their lower chords disposed with their vertical flanges substantially in the plane of the outside dimension of the car. Application of the teachings of said patent to the cars of the type last 30 mentioned involves serious and undesirable alterations at the lower edges of the plates and necessitates undesirable openings or exposure of parts to permit the attachment of the lower edges of the side wall plates to the more widely spaced 35 vertical flanges of the lower chord. If the undesirable openings through the plates are to be avoided, then the lower edges of the stakes at the point of attachment to the lower chord must be exposed to the interior of the car, or if this 40 is to be avoided, then some special expensive and unwanted covering plates or the like, must be provided.

Accordingly, the present invention provides a 45 side wall construction which is adapted for application to cars having their lower frame chords more widely spaced than are the chords of the car disclosed in said patent, whereby cars of this type may be built as new cars or the walls hereof 50 may be applied to that type of car having maximum capacity with internal stakes to provide the added advantage of protection of the stakes, without in any wise altering or changing the under-frame construction. When this invention is applied to previously existing cars it is only necessary to remove the old walls and apply the wall 55 construction of this invention which can be immediately attached to the under chord and frame parts from which the old wall was removed. The original gusset plates placed internally of the car are perfectly adapted for attachment to the new 60 wall and if desired, the upper chord can also be used. Furthermore, the new wall construction of this invention is provided with slanting shedding surfaces for all of the internally projecting portions 65 thereof whereby complete and efficient unloading of the car is realized when the car is inverted by unloading apparatus now in common use.

The nature of this invention will be better 70 understood by referring to the accompanying

drawings, which illustrate, by way of example, one preferred embodiment thereof, and in which;

Figure 1 represents a side elevational view of the body of a hopper car constructed in accordance with this invention;

Figure 2 is an enlarged cross sectional view showing a portion of the wall construction and taken on the line A—A of Figure 1 and looking in the direction of the arrows;

Figure 3 is an enlarged vertical cross sectional view taken on the line B—B of Figure 1, and looking in the direction of the arrows;

Figure 4 is an enlarged cross sectional view showing the wall construction taken on the line C—C of Figure 1 and looking in the direction of the arrows; and

Figure 5 is a perspective view with portions of the car frame broken away and disclosing the construction of the side wall plate.

By referring to the drawings it will be noted that the bottom chord 11 is in the form of an angle support with the vertical flange thereof positioned substantially in the plane of the maximum outward dimension of the car. The upper chord 12 is of usual construction having a downwardly extending flange 13, disposed inwardly for attachment to the inner surface of the stakes and to provide an attaching flange for the upper edge of the side wall plates which are disposed inwardly as clearly illustrated in Figure 5.

Side wall plates 14 may be of any suitable width depending upon the desired construction of the car and as here illustrated, the three end plates are of less width than the central plates. It is preferable, but not necessary, that each of the plates be of sufficient width to occupy the space between stakes and therefore the width of the plates will be selected according to the number and spacing of the stakes required for the desired frame construction. Each of the plates has a top flange 15 disposed in the inner plane and side flanges 16 and 17 respectively, also disposed in the inner plane and which are made continuous with the main panel 18 of the wall plate by offsetting surfaces 19 and 20, preferably inclined, as shown. It is highly desirable to have the upper surface 20 inclined so as to provide the necessary shedding action when the car is inverted in the usual unloading operation.

The lower edge 21 of the plate is disposed in the same outer plane as the main panel 18. In other words, the panel continues straight downwardly and terminates at a point for ready attachment to the vertical flange of the lower chord 11. Side flanges 16 and 17 are inclined outwardly at their lower portions as at 22 and 23 respectively, so as to continuously join with the lower edge 21 of the plate which is in the outer plane. As illustrated in Figure 2, it will be noted that the plates are adapted to be placed side by side, to form the continuous wall of the car and are preferably mounted with their side flanges 16 and 17 in overlapping relation and attached by suitable means, such as rivets 24, to the vertical stakes 25.

The stakes of this invention are preferably constructed in the manner illustrated in the drawings so as to comprise an angle construction having a flange 26 in the inner plane for the attachment of the wall plates and the flange 13 of the upper chord 12, and an outwardly extending flange 27 which terminates in the plane of the maximum permissible dimension of the car. It will be noted that the flange 27 extends slightly beyond the plane of the main panel 18 of the

wall plates as a slight clearance must be left on the plates for rivet heads, plates, and the like.

At the lower portion of the stake, the flange 26 is inclined outwardly as at 28 so as to terminate in an outer plane as at 29 for attachment to the vertical flange of the lower chord 11. The outer edge of the outwardly extending flange 27 preferably continues straight down so as to provide a reinforcement 30 for the portion 31 of the stake. In order to add additional strength, an enlargement 32 may be provided along the edge of the flange 27 throughout the central and upper portion thereof.

As shown in Figures 3 to 5 inclusive, the inner plate 33 which is now utilized in the standard car constructions of the type herein referred to, may be retained exactly as before, so as to provide a shedding surface and a covering and protecting plate for the lower chord 11. The upper edge of the vertical flange of the lower chord 11 may be covered by extending the plate 33 or it may be protected by paint or other material which may be applied thereto. This narrow edge can be readily protected in practice so as to avoid exposure of the frame parts to the load in the car.

From the above construction, it will be noted that a car of substantially maximum capacity is provided by virtue of the fact that the wall plates are for the most part disposed in the plane of the maximum width of the car while at the same time, the side wall stakes are exterior of the plates and are thereby entirely protected from the contents of the car and the damage and deterioration occasioned when the stakes are placed internally.

Furthermore, this invention differs from the invention illustrated in Patent No. 1,623,591, above referred to in that it is particularly adapted for the type of car having more widely spaced lower chords of the type above referred to, so that the side wall plates extend directly downwardly for attachment to the upper flange of the chord in a manner to afford a simple and efficient construction with the stakes maintained externally of the walls.

Although it is not specifically illustrated, it will readily appear that the wall construction here provided can be supported with the standard gusset plates now installed in the type of car having internal stakes and outwardly placed wall plates so that it is only necessary in converting standard car constructions, to remove the old wall and attach the new wall construction. In newly constructed cars, no alteration is necessary in the underframe construction, gusset plates and like standard parts, as the wall lends itself perfectly to application to the standard car constructions of the type referred to.

I claim:

1. In a railway car, a wall construction comprising stakes, a bottom chord having a portion disposed in a plane substantially at the outer face of said stakes and a wall portion comprising a plate having its central and bottom edge portions disposed outwardly substantially in the plane of the outer face of said stakes and inwardly and laterally extending side edge portions attached to the inner face of said stakes, said bottom edge portion being attached to said portion of said chord.

2. In a car of the class described, a wall construction comprising side stakes, a bottom chord having a face disposed in a plane substantially at the outer face of said stakes and a wall having substantially its entire main portion and bottom

edge disposed in a plane substantially at the outer face of said stakes and being provided with spaced portions at the location of said stakes in a plane substantially at the inner face of said stakes and attached to said stakes, and said wall having its bottom edge attached to said portion of said chord.

3. In a railway car, a wall construction comprising top and bottom chord members, side stakes, and wall plates enclosing the spaces defined by said chords and side stakes, said top chord having a vertical flange disposed substantially in the plane of the inner face of said stakes and said bottom chord having a vertical flange disposed in a plane substantially at the outer face of said stakes, the top and bottom of said stakes being attached to said flanges respectively and externally thereof, said wall plates having their main portions disposed substantially in the plane of the outer face of said stakes with inturned top and side edges for attachment to said stakes and the flange of said upper chord respectively and a lower edge disposed substantially in the plane of the main portion thereof and attached to said flange of said lower chord member.

4. A side stake for railway cars of the character described comprising an inner flange, and a transverse flange at right angles to said inner flange, said inner flange being adapted for attachment to a top chord member and a wall plate, said inner flange, at the bottom portion of said stake, extending diagonally outwardly and terminating in a plane outwardly of the plane of said inner flange, and presenting means for attachment to a bottom chord in a plane near the plane of the outer edge of said stake.

5. A side stake for railway cars of the character described comprising an inner flange, and a transverse flange at right angles to said inner flange, said inner flange being adapted for attachment to a top chord member and a wall plate, said inner flange, at the bottom portion of said stake, extending diagonally outwardly and terminating in a plane outwardly of the plane of said inner flange, and presenting means for attachment to a bottom chord in a plane near the plane of the outer edge of said stake, said transverse flange being provided throughout a portion of its length with a reinforcing enlargement on its outer edge.

6. A car side stake having a flange at its inner plane for attachment of a side wall plate and a surface in a plane outwardly of its inner plane for attachment to a bottom chord, said outer plane being near the outer plane of said stake.

7. In a car of the character described, the combination of a side stake and upper and lower chords, said upper chord and stake having cooperating and attached portions in an inward plane and said lower chord having cooperating and attached portions in a plane outwardly of said inward plane.

8. In a car of the character described, the combination of a side stake and upper and lower chords, said upper chord and stake having cooperating and attached portions in an inward plane and said lower chord having cooperating and attached portions in a plane outwardly of said inward plane, and means on said stake throughout a portion of its height for attachment of a wall plate at the inner plane thereof, and means at the bottom of said stake for attachment of said wall plate in said outer plane.

9. A wall for a railway car comprising an upper chord having a vertical flange, a lower chord having a vertical flange, said flanges being in

- spaced apart parallel planes, and wall sheets attached to said flanges respectively, the marginal portions of the sheets being substantially in the plane of the upper flange for the major portion 5 of their length and in the plane of the lower flange for the remainder of their length, the central portions of the sheets between said marginal portions being substantially in the plane of the lower flange for the major portion of their length 10 and in the plane of the upper flange for the remainder of their length.
10. A wall for a railway car comprising an upper chord having a vertical flange, a lower chord having a vertical flange, said flanges being in spaced apart parallel planes, and wall sheets attached to said flanges respectively, the marginal portions of the sheets being substantially in the plane of the upper flange for the major portion 15 of their length and in the plane of the lower flange for the remainder of their length, the central portions of the sheets between said marginal portions being substantially in the plane of the lower part for the major portion of their length and in the plane of the upper part for the remainder of their length, a stake secured to the upper and lower chords, respectively, and means to secure 20 said marginal portions and the stake together.
11. A wall for a railway car comprising an upper chord having a vertical flange, a lower chord having a vertical flange, said flanges being in spaced apart parallel planes, wall sheets attached to said flanges respectively, the marginal portions of the sheets being substantially in the plane of the upper flange for the major portion of their length 25 and in the plane of the lower flange for the remainder of their length, the central portions of the sheets between said marginal portions being substantially in the plane of the lower part for the major portion of their length and in the plane of the upper part for the remainder of their length, and a stake secured to said chords, respectively, and to adjacent wall sheets.
12. A wall for a railway car comprising an upper chord, a lower chord, and wall sheets, each sheet comprising marginal portions at the sides and top thereof and a central portion in a spaced apart substantially parallel plane, the lower parts 30 of the side marginal portions merging into the plane of the central portion, the upper part of the central portion merging into the plane of the marginal portions, the top marginal portions of the wall sheets being secured to the top chord and the lower parts of the central portions of 35 the wall sheets being secured to the lower chord.
13. A wall for a railway car comprising an upper chord, a lower chord, and wall sheets, each sheet comprising marginal portions at the sides and top thereof and a central portion in a spaced apart substantially parallel plane, the lower parts 40 of the side marginal portions merging into the plane of the central portion, the upper part of the central portion merging into the plane of the marginal portions, the top marginal portions of the wall sheets being secured to the top chord, the lower parts of the central portions of 45 the wall sheets being secured to the lower chord.
14. A wall for a railway car comprising an upper chord having an attaching part, a lower chord having an attaching part, said parts being in spaced apart parallel planes, and wall sheets attached to said parts, respectively, the marginal portions of the sheets being substantially in the plane of the upper part for the major portion of 50 their length and in the plane of the lower part for the remainder of their length, the central portions of the sheets between said marginal portions being substantially in the plane of the lower part for the major portion of their length and in the plane of the upper part for the remainder of their length, a stake secured to the upper and lower chords, respectively, and means to secure 55 said marginal portions and the stake together.
15. A wall for a railway car comprising an upper chord having an attaching part, a lower chord having an attaching part, said parts being in spaced apart parallel planes, and wall sheets attached to said parts, respectively, the marginal portions of the sheets being substantially in the plane of the upper part for the major portion of 60 their length and in the plane of the lower part for the remainder of their length, the central portions of the sheets between said marginal portions being substantially in the plane of the lower part for the major portion of their length and in the plane of the upper part for the remainder of their length, and a stake secured to said chords, respectively, and to adjacent wall sheets.
16. A wall for a railway car comprising an upper chord having an attaching part, a lower chord having an attaching part, said parts being in spaced apart parallel planes, and wall sheets attached to said parts, respectively, the marginal portions of the sheets being substantially in the plane of 65 one of said parts for the major portion of their length and in the plane of the other of said parts for the remainder of their length, the central portions of the sheets between said marginal portions being substantially in the plane of said other of said parts for the major part of their length and in the plane of the other of said parts for the remainder of their length, the major part of the length of the marginal portions and the central portions of said sheets respectively, being in different planes, and a stake secured to said chords, respectively, and to adjacent wall sheets.
17. In a railway car, a wall construction comprising top and bottom chords and stakes, said stakes being attached to said chords, said bottom chord having a portion disposed in a plane substantially at the outer face of said stakes and a wall plate between said stakes, said wall plate having substantially its entire main portion including its lower edge, in a plane substantially at the outer face of said stakes and attached to the bottom chord, and being provided with inturned side and top edges attached to said stakes and top chord respectively.

DAVID HINDAHL.
